UNITED STATES PATENT OFFICE.

CURT SCHMIERS, OF WHITEWATER, WISCONSIN.

CHILD'S VEHICLE.

Application filed June 25, 1923. Serial No. 647,581.

To all whom it may concern:

Be it known that I, CURT SCHMIERS, a citizen of the United States, and resident of Whitewater, in the county of Walworth and State of Wisconsin, have invented certain new and useful Improvements in Children's Vehicles; and I do hereby declare that the following is a full, clear, and exact description thereof.

10 This invention relates to toys, and is particularly directed to a vehicle adapted to be propelled by foot power.

Objects of this invention are to provide a toy which is adapted to support the operator and permit him to propel and steer the apparatus, to provide a device so constructed that it simulates an aeroplane in its general contour, to provide an apparatus in which the steering is accomplished by extremely simple means, and to provide an apparatus in which the wings are hingedly mounted upon the sides of the body portion and so organized that they may be readily folded downwardly to permit easy transporting or storing of the apparatus.

An embodiment of the invention is shown in the accompanying drawings, in which:—

Figure 1 is a longitudinal, sectional view through the apparatus.

30 Figure 2 is a bottom view of the device.

Figure 3 is a sectional view on the line 3—3 of Figure 1.

Figure 4 is a sectional view on the line 4—4 of Figure 3.

35 The apparatus comprises a body portion 1 formed from sheet metal and pressed into shape so as to provide a rounded back portion tapering towards the front and rear, and downwardly extending marginal flanges, the margins of the entire device being preferably beaded, as indicated at 2, so as to provide finished edges. An upstanding cockpit 3 is provided, which may be integral with the body portion 1, as shown in the

40 drawings, or separate therefrom and riveted thereto. This cockpit has an upper beaded edge 4 to give a finished appearance and to protect the occupant from damage from the raw edges of the sheet metal. The 45 upward end of the body portion extends across the bottom, as indicated at 5, and houses a block 6 of any suitable material, preferably wood, as illustrated in the drawings. Within this block of wood a support-

ing screw 7 is passed and revolvably supports 55 a propeller 8.

A pair of main wings 9 are hingedly mounted upon the sides of the body portion, as may be seen from Figure 3. A convenient way of securing this pivotal mounting 60 is by forming an upstruck portion 10 upon the body and providing aligned apertures upon opposite sides thereof. These apertures are adapted to receive the hooked ends 11 of the reinforcing rod 12 for the marginal bead of the wings, such rod being conveniently extended beyond the beaded edge and bent inwardly as shown in Figure 4. In order to support the wings temporarily in an outwardly extending position, a similarly formed upstruck portion 13 is provided for each wing and constitutes a hinged bearing for the rod or strut 14. The inner end of the rod, as indicated at 15, is provided with a hook or bent end which hooks into 75 an apertured lug 16 carried by the body portion and is adapted to be removed therefrom to permit the downward folding of the wings, as indicated in dotted lines in Figure 3. A second smaller pair of wings 17 are 80 provided adjacent the rear portion of the device and project a slight distance outwardly from the body portion.

85 A longitudinally extending bracing strip 18 is riveted to the under side of the body portion and extends forwardly to the edge of the cockpit. At this point it is offset, as indicated at 19 in Figures 1 and 2, and supports an upholstered seat 20. A transverse brace strip 21 is riveted at its central 90 portion to the outer end of the portion 19 of the bracing strip and is preferably arcuate, as shown in Figure 2. Its ends are riveted to the sides of the body portion. The strips 19 and 21 form a secure support for the seat.

95 The device is carried by a running gear consisting of a rear wheel 22 carried by a fork 23 rigidly secured to the under side of the strip 18, as may be seen from Figure 1. 100 The forward portion of the apparatus is provided with a bearing plate 24 which may be secured to an extension of the block 6, if desired. This bearing plate has pivotally secured thereto by means of a king bolt 25 the transverse portion of the fork 26 for the front wheels. This transverse portion is rigidly secured to a rearward exten-

sion 27 which projects upwardly at a slight angle and forms the steering post 28 for a hand wheel 29. A pair of front wheels 30 are rigidly mounted upon a transverse shaft 5 31 carried by the fork 26 and provided with offset or crank portions 32 adapted to receive the feet of the operator.

It will be seen that the operator may readily seat himself upon the upholstered seat 10 20 with his feet projecting downwardly through the device and resting upon the cranks 32, whereby propulsive motion may be given the device. The steering is accomplished by rocking motion of the hand 15 wheel which closely approximates a twisting motion thereof as the hand wheel is rigidly secured to the stem 28 and such stem is in turn rigidly secured to the fork 26. If desired the channel bearing plate 24 may have 20 its rear flange cut out to provide stops 33 to limit the rocking motion of the portion 27 of the hand wheel stem.

It will be seen that a toy has been provided which simulates in appearance an aeroplane, which may be readily operated by a 25 child, and which is of extremely simple and sturdy construction.

It will further be seen that due to the hinged mounting of the wings, when the device 30 is not in use, the wings may be readily folded downwardly against the body portion and thus facilitate storing or transporting of the device.

Although one form of the invention has 35 been described in considerable detail, it is to be understood that the invention may be variously embodied and is to be limited only as claimed.

I claim:—

40 1. A child's vehicle having a body portion simulating in appearance an aeroplane, a rear supporting wheel, a pivot pin, a forward fork pivotally mounted on said pin, a pair of wheels carried thereby, a pedal 45 means for operating said wheels, a steering wheel offset from the pivot pin of said fork and rigidly attached thereto, said body por-

tion including a pair of pivotally mounted wings adapted to be folded downwardly when not in use. 50

2. A child's vehicle comprising a body portion formed of pressed sheet metal and having a central opening and an upstanding cockpit surrounding said opening, a seat positioned within said opening, wings pivotally carried by the outer portion of said body and adapted to be rocked into outwardly projecting position or to be folded downwardly against said body portion, a rear supporting wheel, a forward fork pivotally joined to said body portion, a transverse shaft provided with cranks carried by said fork, a pair of wheels rigidly secured to said shaft, and steering means projecting laterally from said fork and upwardly 60 through said cockpit. 65

3. A device of the class described comprising a body portion formed of pressed sheet metal and having an approximately centrally located aperture, a cockpit extending upwardly adjacent said aperture, a longitudinally extending reinforcing strap secured to the under side of said body portion and projecting into said aperture, a cross strap secured to said body portion and to 70 said longitudinal strap and projecting across said aperture, a seat carried by said straps and located within said aperture, a rear wheel having a supporting fork secured to said longitudinal strap, a forwardly positioned pair of wheels, a shaft provided with cranks and rigidly secured to said wheels, a fork mounted upon said shaft and pivotally engaging said body portion, means for rocking said fork, a reinforcement positioned within the forward portion 75 of said body, and a propeller pivotally supported from said reinforcement. 80

In testimony that I claim the foregoing I have hereunto set my hand at Whitewater, 90 in the county of Walworth and State of Wisconsin.

CURT SCHMIERS.
